UNITED STATES PATENT OFFICE.

GEORGE H. E. TROUVELOT AND HENRY B. HILL, OF CAMBRIDGE, MASS.

TOGGLE-JOINT FOR PRESSES, &c.

SPECIFICATION forming part of Letters Patent No. 244,950, dated July 26, 1881.

Application filed June 8, 1881. (No model.)

To all whom it may concern:

Be it known that we, GEORGE H. E. TROUVELOT and HENRY B. HILL, both of Cambridge, in the county of Middlesex and State of Massachusetts, have invented a new and useful Improvement in Toggle-Joints for Presses or Punching-Machines, of which the following is a description, reference being had to the drawings accompanying and forming part of this specification.

This form of toggle-joint is particularly intended as a means of applying pressure in copying-presses; and the invention has for its object, first, the production of greater pressure than can be obtained by means of a screw-press of the same size; second, variation at will in the amount of pressure applied, and adjustment of the distance of the platen from the floor of the press according as may be required by the thickness of the article to be pressed; third, removal of strain from the supports of the arms of the toggle-joint during the application of pressure and effectiveness in the application of pressure; and, fourth, simplicity and cheapness of construction and ready separation and readjustment of the working parts.

To these ends the invention consists in forming the upper arm of the toggle-joint by an enlargement of the end of the lever used to straighten the joint, and in supporting said arms by means of trunnions resting in hooks or slots which are curved in an arc which has for its generating-point the center of the supported trunnion; also, in providing the lower part of the lever or handle with a lug or projection, which bears against the lower arm of the toggle-joint below its supporting trunnions and acts to cause the set of the toggle-joint, 40 when it is straightened, and in making the lower arm of the toggle-joint in three parts, one of which is provided with an external screw-thread working in an internal screw-thread in a nut or jacket, which forms the second part of this lower arm, and the lowermost of which parts forms the lower butting-piece of the toggle-joint, is connected to the nut or jacket in such a manner that it will not turn with the nut or jacket when the latter is rotated in a horizontal plane, and supports the

platen by means of trunnions resting in hooks or slots.

The invention also consists in certain details of construction, which will hereinafter be more fully described.

In the accompanying drawings, Figure 1 is a vertical sectional view of the toggle-joint and lever. Fig. 2 is a longitudinal sectional view of the device for securing the arch to the plate of the press. Fig. 3 is a transverse sectional view of the same. Fig. 4 is a top view of the lever. Fig. 5 is a side elevation of the entire system, showing the lever, the toggle-joint, and the platen; and Fig. 6 is a bottom view of the lever.

In these several figures the same letters refer to the same parts.

Referring to the drawings, A is a part of the arch of the copying-press, which arch is about of the same height as the arch in screw-presses of the same size, and is preferably made of the girder form.

B is the lever used to straighten the toggle-joint, which lever is preferably made of one piece of metal and as lightly as is consistent with strength, and is provided with a suitable handle, a portion of which only is shown in the drawings. The other end of this lever is enlarged and formed as shown, so that a part of this end forms the upper arm, C, of the toggle-joint. The upper surface of this arm bears against the under side of the arch, and the under side of the lever B is cut away, as shown in Figs. 5 and 6, so as to form a recess, D, for the reception of the end of the lower arm of the toggle-joint. From each side of this recess extend projections E E', in each of which is a slot or recess, L, for the reception of the trunnions which support the lower arm of the toggle-joint, as shown in Fig. 5. The distance between these projections must be sufficient to allow of the lever being disconnected from the arm.

In order that when pressure is applied all strain may be removed from the bearings which form the fulcrum of the lever B, and to secure simplicity of construction and ready separation of the parts, we support this lever by means of trunnions, which are supported upon suitable curved hooks or slots. These trun-

nions may extend from the arm C on either side, as shown in the drawings at G G', and rest in curved hooks H H', extending from the under side of the arch, or may be formed from 5 narrow stepped shoulders on the extremities of these curved hooks H H', which engage in slots or recesses cut on either side of the arm, so as to form courseways for the trunnions.

The projecting hooks may be cast in one 10 piece with the arch, and the trunnions G G' may be cast in one piece with the arm C of the toggle-joint. The center of motion of this arm is at the point where it bears against the under side of the arch, and consequently the 15 center of the supporting-trunnion must be the generatrix of the arc of the bearing-surface of the slot or hook; but in order that the trunnions may be easily removed, the curve is a volute. The thickness of the upper arm from 20 its butting-surface to the trunnions need only be sufficient to enable the arm in one position alone to be raised up from and removed from the supporting hooks or slots, so that all necessary working positions of the arm will be 25 permitted, and yet the parts will admit of being separated and of being expeditiously put together, and consequently the upper arm, C, may be so short that the arch of the press will not have to be any higher than in a screw 30 copying-press of the same size.

The lower arm of the toggle-joint is made in three parts—viz., the upper butting piece or screw, H'', the lower butting-piece, I, and a jacket or nut, K, which connects these two 35 parts. The upper piece or screw, H'', is a rod, which is rounded on its upper end, fits within the recess D in the lever B, and bears against the under surface of the upper arm, C. This arm is also supported by trunnions, which extend from each side of the screw H'' and bear 40 in slots or recesses L L' in the side projections, E E', of the lever B. These slots or recesses are curved in an arc whose center is the center of motion of the lever B, and are slightly 45 wider than the diameter of the trunnions, so that when the toggle-joint is straightened the trunnions will rise up from their bearing-surfaces and thus be relieved from strain.

Instead of placing trunnions on the screw, 50 projections which will act as trunnions may be formed upon the inner side of the side pieces, E E', and each of these projections will rest in a slot on the side of the screw, opposite to one another. The screw H'' fits into the jacket or 55 nut K, and its thread engages with an internal screw-thread in the jacket or nut K. This thread is made in any suitable manner. In the drawings it is shown as babbitted into the jacket, which is a convenient manner in small presses. 60 Upon the outside of the jacket is a milled rim, N, by means of which it may be rotated in a horizontal plane. The lower butting-piece, I, cannot rotate when the jacket or nut K is turned, and this is effected by securing the 65 piece I to the jacket or nut K in any suitable manner which will accomplish this result. A

convenient method is shown in Fig. 1, which consists in attaching to the piece I a stem, a, provided with a flange, b, which, by means of Babbitt metal around the stem a, secures the 70 piece I to the jacket or nut K, and the latter is permitted to rotate.

The platen P is supported by means of curved hooks R R', which rest upon trunnions S S', on each side of the piece I, and which may be 75 cast in the same piece with it or secured thereto in any suitable manner. The converse of this method of support—viz., placing trunnions or the equivalents thereof on the platen and slots or recesses on the piece I—may be used. 80 The bearing-surfaces of the supporting hooks, slots, or recesses R R' are in the curve of a volute which has for its center the center of the supporting-trunnion.

To the under side of the lever B is attached 85 a projection or lug, T, which bears against the lower arm of the toggle-joint below its supporting-trunnions, and this projection acts, when the lever B is depressed, to assist in straightening the joint and to increase the effectiveness of the pressure, while at the same time removing strain from the trunnions. 90

The arch of the press may be secured to the floor of the same in any suitable manner. A desirable manner is that shown in Figs. 2 and 95 3, in which the arch is provided with a tenon, C, which fits within a mortise, d, on the base-plate, and is secured therein by means of a wedge-shaped key, f, which is driven through a cored opening, preferably of rectangular section, against an inclined surface, e, on the under side of the base-plate. 100

What we claim as our invention, and desire to secure by Letters Patent of the United States, is—

1. In presses or punching-machines, a toggle-joint for causing the movement of the platen or punch, which toggle-joint has both of its arms supported by means of trunnions or their equivalents resting in hooks or slots, and in which the upper arm of the toggle-joint forms part of the lever which is used to straighten the joint, substantially as and for the purpose set forth. 110

2. In presses or punching-machines in which pressure is applied by means of a toggle-joint, trunnions or their equivalents resting in hooks or slots, and thus supporting the arms of the joint and the platen or punch, substantially as and for the purpose set forth. 115

3. Slots or hooks in which the trunnions supporting the arms of the toggle-joint and the platen rest, which slots or hooks have their bearing-surfaces in arcs which have for their generating-points the centers of the supported trunnions, and which slots are slightly wider than the supported trunnions, substantially as and for the purpose set forth. 125

4. The lever B, having one end enlarged, so as to form the upper arm of the toggle-joint, 130 and provided at said end with a recess for the reception of the lower arm of the toggle-joint

and with side projections having curved slots or recesses therein, substantially as and for the purpose set forth.

5. The combination of the lever B, constructed as described, the trunnions G G', attached to said lever, the curved hooks H H', attached to the under side of the arch and supporting said trunnions, the lower arm of the toggle-joint, and trunnions attached thereto and resting in curved slots or recesses L L' in the lever B, substantially as and for the purpose set forth.

6. A toggle-joint for presses or punching-machines, having its lower arm constructed in 15 three parts, connected as described, whereby the length of the arm may be varied as may be desired, substantially as and for the purpose set forth.

7. The combination of the screw H'', the 20 jacket or nut K, provided with an internal screw-thread and receiving the screw H'', and the lower butting-piece, I, supporting the platen and connected to the jacket, as described, whereby the jacket can be rotated in a plane 25 at right angles to the axis of the lower arm

without rotating the butting-piece I, substantially as and for the purpose set forth.

8. The combination of the lower butting-piece, I, jacket or nut K, stem a, flange b, and Babbitt metal, substantially as and for the 30 purpose set forth.

9. The combination of the lower butting-piece, I, provided with the trunnions S S', and the platen P, provided with the curved hooks R R', resting upon the trunnions, substantially 35 as and for the purpose set forth.

10. The combination, with the lever B, of the projection T, extending from the under side of said lever and bearing against the lower arm of the toggle-joint, below its supporting-trunnions, substantially as and for the 40 purpose set forth.

In witness whereof we have hereunto set our hands in the presence of the subscribing witnesses.

GEORGE H. E. TROUVELOT.

HENRY B. HILL.
